UNITED STATES PATENT OFFICE.

HENRY G. MORRIS, OF PHILADELPHIA, PENNSYLVANIA.

FLYING-MACHINE.

1,073,277.

Specification of Letters Patent. Patented Sept. 16, 1913.

Application filed August 20, 1908. Serial No. 449,513.

To all whom it may concern:

Be it known that I, HENRY G. MORRIS, a citizen of the United States, residing at the city of Philadelphia, in the county of Philadelphia and State of Pennsylvania, have invented certain new and useful Improvements in Flying-Machines, of which the following is a specification.

The principal objects of the present invention are to provide a device for aerial navigation which shall remain comparatively steady and balanced under conditions of use; to provide for raising the device into the air without the necessity of a preliminary horizontal run or flight; to provide for the simple, reliable and strong construction of the device; and generally, to provide a reliable, efficient and conveniently operated device or machine for aerial navigation.

The invention will be claimed at the end hereof but will first be described in connection with the embodiment of it selected for illustration in the accompanying explanatory drawings in which—

Figure 1, is a top or plan view with the upper braces removed. Fig. 2, is a side view, Fig. 3, is a transverse sectional view and Fig. 4, is a view drawn to an enlarged scale and partly in section illustrating the fixed crank shaft of the motor and its accessories.

In the drawings 1, is the motor or power device and its rotor is sufficiently heavy to constitute or operate as a gyroscope and thus add stability to the whole structure. The motor 1, is provided with cylinders 2, mounted as on a base 3, so as to rotate and drive the shaft 4, and the base 3, and the cylinders 2, in respect to the fixed crank shaft at the top of Fig. 4. The cylinders are of the internal explosion variety and the oil which they consume may be carried in the oil tank 5, and fed to them as by a connection 6. The revolving parts of the described engine by reason of their mass and high speed of revolution constitute the gyroscope.

7, and 8, are fans of which two are shown in the present instance, but the number is not material and may be increased or diminished. These fans operate vertically and their purpose is to lift the machine or device. The fans are revolvably mounted in holders 9, carried by the structure which in the present instance constitutes the oil tank 5, and is of generally 8-shape in plan. The

part 5, may simply constitute a frame but by making it a hollow tubing it is strong enough to properly carry the fan or fans and it is light and can be used as an oil tank. 60 The motor 1, drives the fans by means of the connections 10 and 11, shown to consist of belts and pulleys, the belt 10, being crossed so that the fans are revolved in opposite directions, thus opposing any tendency that 65 might exist for the machine to turn as a whole. The frame 5, carries a vertical partition or keel 12, and the horizontal partition or plane 13.

14, are braces arranged in generally diamond form. 15, is a seat or basket for the aviator or operator. It is suspended from the sides of the frame 5, by two of the braces 14, and from the front and back parts of the frame by the supports 16 and 17. 75

18, is a rudder for guiding the device.

In use the motor and fans are started and the latter operate to lift the device even from a position of rest up into the air. The motor by reason of the character of its rotor operates as a gyroscope and thus establishes a position of equilibrium which the device tends to maintain. The speed of the fans determines the rise and fall of the device. Movement in horizontal directions is 85 accomplished by permitting the plane 13, to operate upon the air as an aeroplane. The operator may change the balance of the device by slightly shifting his position and the rudder affords means for directing the 90 flight or direction of motion.

What I claim is:

1. A device for aerial navigation comprising a horizontal tubular frame constituting a rotary fan support, a fan revolvably 95 mounted on said frame, a vertical keel above said frame, a horizontal plane connected with said frame, a motor suspended from the frame and having a rotor constituting a gyroscope, connections between the fan and 100 motor, and a support for the operator suspended from the frame, substantially as described.

2. A device for aerial navigation comprising an 8-shaped horizontal frame provided 105 with an upwardly extending keel or partition and a horizontally extending plane, rotary fans mounted in the openings in the frame, a motor connected with the frame and having a rotor adapted to operate as a 110 gyroscope, driving connections between the motor and fans, and a support for the op-

erator suspended from the side and front and rear portions of the frame, substantially as described.

3. A heavier than air device for aerial navigation comprising the combination of 5 a tubular ring-like frame having a fan opening through it, a rotary fan arranged at said opening, a vertical keel above the frame, an aeroplane flush with the frame 10 and having a fan opening, a motor suspend-

ed from the frame, connections between the fan and motor, and a support for the operator.

In testimony whereof I have hereunto signed my name.

HENRY G. MORRIS.
